Primary Examiner — Lauren R Calve*(74) Attorney, Agent, or Firm* — Nixon & Vanderhye P.C.(57) **CLAIM**

The ornamental design for a handle for fluid and gas coupling, as shown and described.

DESCRIPTION

FIG. 1 is a perspective view of a handle for fluid and gas coupling according to the present design;

FIG. 2 is a second perspective view thereof;

FIG. 3 is a side view thereof, the opposite side being a mirror image;

FIG. 4 is a front view thereof;

FIG. 5 is a rear view thereof;

FIG. 6 is a top view thereof; and,

FIG. 7 is a bottom view thereof.
